(57) **CLAIM**

The ornamental design for an outdoor furniture surface protector, as shown and described.

DESCRIPTION

FIG. 1 is a bottom perspective view of an outdoor furniture surface protector of my new design;

FIG. 2 is a top perspective view thereof;

FIG. 3 is a front side view thereof;

FIG. 4 is a rear side view thereof;

FIG. 5 is a right side view thereof;

FIG. 6 is a left side view thereof;

FIG. 7 is a bottom view thereof;

FIG. 8 is a top view thereof;

FIG. 9 is an environmental bottom perspective view thereof; and,

FIG. 10 is an environmental top perspective view thereof. The dash-dash broken lines represent portions of the outdoor furniture surface protector, and form no part of the claimed design. The dash-dot broken lines illustrated in FIG. 9-10 depict environment, and form no part of the claimed design.

1 Claim, 8 Drawing Sheets
